(57) **CLAIM**

The ornamental design for a “insertion detection,” as shown and described.

DESCRIPTION

FIG. 1 is a top view of an insertion detection showing a new design;

FIG. 2 is a bottom view thereof;

FIG. 3 is a back view thereof;

FIG. 4 is a front view thereof;

FIG. 5 is a left view thereof;

FIG. 6 is a right view thereof; and,

FIG. 7 is a perspective view thereof.

The broken line showing of structural features is included for the purpose of illustrating non-claimed subject matter and forms no part of the claimed design.
